UNITED STATES PATENT OFFICE

2,028,176

BRUSH RIGGING AND END CAP ASSEMBLY
FOR SURGICAL MOTORS AND THE LIKE

Howard A. Whiteside, New York, N. Y.

Application July 26, 1932, Serial No. 624,739
Renewed March 23, 1935

56 Claims. (Cl. 171—324)

The present invention relates to brush rigging and end cap assemblies for surgical motors and the like, and is more particularly directed toward structures of a type suitable for employment in such commutator type motors wherein the motor shaft and spindle of the hand piece are hollow so that the fastening and release of a tool may be controlled by a clutch rod which passes through the motor armature shaft and hand piece spindle, or wherein the shaft is solid. Hand pieces wherein the coupling and uncoupling of the tool are under the control of the clutch rod passing through the spindle are generally known as Doriot hand pieces, and the present invention is more particularly directed toward the rear end of a motorized Doriot hand piece wherein the motor for operating the tool in the hand piece is directly connected to the hand piece so that the motor and hand piece form a single instrument capable of being held in the hand for surgical operations and wherein the adjustment of the clutch for the tool is performed by the clutch rod extending out through the rear of the motor. Certain features of the present invention, however, are capable of general application to small motors, whether of the type wherein a hollow armature shaft is employed or whether of the type wherein a solid armature shaft is used which does not protrude through the end cap of the motor. In such motors, a modified arrangement of bearings may be employed.

An object of the present invention is to provide a brush rigging for surgical motors in which radial spring-pressed brushes cooperative with a cylinder type commutator are carried in a ring made out of insulating material secured on the end of the motor housing. This brush rigging may be so arranged that the brush carrying disk is cut away to permit access to the commutator for purposes of cleaning or the brush boxes may be provided by radially drilling the disk and axially extending metallic inserts. The brushes may be removed for cleaning and replacement without disturbing the neutral point adjustment of the brushes.

The present invention also contemplates the provision of end cap and brush rigging assembly more particularly for surgical motors and wherein the brush carrying disk secured to the motor housing carries the end cap. The end cap housing preferably has a long bearing on the outer surface of the brush rigging carrying disk and is clamped to the brush carrying disk by axially extending members secured to the brush carry-

ing disk and extending through the wall of the end cap. The end cap may then cover the brush rigging and prevent entrance of dirt or moisture. The end cap carries terminals electrically connected with the current supply wires in a flexible cable, and in certain types of motor, it also provides the support for the rear bearing in the motorized hand piece. 5

The present invention relates to improvements in the form of combined brush rigging and end cap assemblies shown in my copending application 580,920, a division of Patent No. 1,836,350. Other and further objects of the invention will appear as the description proceeds.

The accompanying drawings show, for purposes of illustrating the present invention, several of the many possible embodiments in which it may take form, it being understood that the drawings are illustrative of the invention rather than limiting the same. 15

Figure 1 is an elevational view of a complete motorized hand piece; 20

Figure 2 is an enlarged longitudinal sectional view through the rear end of the motorized hand piece showing one form of brush rigging and end cap assembly; 25

Figure 3 is a section taken on the line 3—3 of Figure 2 and showing particularly the brush rigging and brush supporting disk;

Figure 4 is an elevational view taken in the direction of the arrow 4 of Figure 2 with parts omitted; 30

Figure 5 is an elevational view taken in the direction of the arrow 5 of Figure 3; parts being in section and other parts being broken away, 35 this figure more particularly showing the securing of the end cap on the brush rigging disk;

Figure 6 is a sectional view taken on the line 6—6 of Figure 2 looking in the direction of the arrow and illustrating the inside of the end cap; 40

Figure 7 is a sectional view similar to Figure 2 showing a different form of construction;

Figure 8 is an elevational view of the rear or left end of Figure 7, with the cover plate omitted and parts broken away to show sections at varying places along the axis of the motor; 45

Figure 9 is a sectional view through the brush rigging and end cap showing the method of fastening these parts together, parts being in elevation and the armature shaft and bearings omitted; 50

Figures 10 and 11 are longitudinal and transverse sectional views with a modified form of motor adapted for use with a central, current supply cord and a disk type commutator, Figure 55

11 being taken on the line 11—11 of Figure 10, and Figure 10 being taken on the broken section line 10—10 of Figure 11;

Figure 12 is a longitudinal sectional view taken on the broken line 12—12 of Figures 13 and 14 and showing a further modified form of motor;

Figures 13 and 14 are respectively end elevational views of the end cap and of the brush rigging and motor body, being taken in the directions of the arrows 13 and 14, respectively, of Figure 12;

Figure 15 is a sectional view on the line 15—15 of Figures 13 and 14 to show the securing of the end cap to the brush rigging disk and the brush rigging disk to the casing; and

Figure 16 is a sectional view on the line 16—16 of Figure 13 to show the off-center current supply cord.

The motorized tool unit which is illustrated in Figure 1 may be considered to consist of a motor A and a hand piece B. The hand piece is adapted to carry a tool such as a drill or grinding wheel indicated at C. The motor portion A contains all of the parts ordinarily found in an electric motor and the speed and direction of rotation of the motor armature may be under the control of a foot controller, such as shown in my co-pending application, Serial Number 580,920.

The motor A has a rigid self-supporting unitary casing 10 of generally cylindrical shape forming a structural part of the motor and directly supporting the field structure. Further details of construction of the motor and hand piece and the operation of assembling the motorized hand piece are set forth in my application for Surgical motors and hand pieces filed on even date herewith as Serial No. 624,738. So far as the parts described in detail herein are concerned, it is sufficient to say that the motor A has a field structure 11 and cylindrical type commutator 12 and hollow or tubular armature shaft 13 which extends out to the left or rear end of the motor. The hollow armature shaft is provided so as to accommodate a clutch rod 14 employed in Doriot type hand pieces.

The motor is provided with a two pole brush rigging carried by an insulating disk 20, one form of which is shown more in detail in Figures 2, 3 and 5. This disk has a slightly reduced portion 21 which extends inside the open left or rear end of the motor casing 10 to which it can be secured by screws 22 after adjustment. The brush holding disk may be considered to consist of a round annulus having a central hole or aperture 24 slightly larger than the commutator 12. The disk is transversely drilled on a diameter as indicated at 25 to accommodate the brushes. Tubular metal sleeves 26 and 27 are pressed into the drilling 25 and each of these tubular sleeves is adapted to support a brush 28, a brush spring 29 and a headless screw 30, the latter being carried in threads tapped into the metal sleeve.

In order to reduce the weight of the parts and permit access to the side of the commutator for cleaning, the disk is cut away in the sides of the brush boxes as appears more clearly in Figure 5. To further lighten the disk and provide for the passage of armature wires, and to maintain the balance of the motor, four holes are drilled into the disk as indicated at 31. The disk 20 may also be provided with a bridging member of about the width of the brush boxes or the aperture 24 may extend all the way through the disk. This bridging member is apertured in the center to accommodate the shaft and may form a bearing for the

shaft when the end cap is removed. If it is to form a bearing it is reamed at the same time as the bearing in the end cap, and to the proper size.

The brush carrying disk also carries a pair of field connection studs 32 and a pair of brush rigging connection studs 34. These studs may conveniently be in the form of long screws passing through tapped holes in the insulating material of the brush disk. The brush boxes 26 and 27 are inserted in place in the brush carrying disk before the holes for the screws 34 are drilled so that each screw will pass through the wall of the brush box, as indicated in Figure 3 thereby locking the brush box in place and electrically connecting it with the screw. The screws 32 and 34 are securely locked in place by nuts 35 and 36, respectively, having heads as indicated for co-operation with a wrench. Two or all of these nuts may have long tubular extensions 35a and 36a chamfered on the edge as indicated. The field wires are passed through the holes 31 and clamped under the nuts 35 so that these studs 32 are connected to the field wires. These four studs are asymmetrically located and extend rearwardly to provide means for securing the end cap above referred to onto the motor and at the same time to provide current connections for the motor armature and field.

In the form of construction shown in Figures 2 and 6, inclusive, the end cap 40 is in the form of a cup-like member adapted to telescope over the outside of the brush carrying disk 20 and abut against the end of the motor casing 10. This end cap carries an adjustable bearing 41 which may include, as shown in Figure 2, a metal sleeve 42 threaded into the end cap 40 and an arguto wood sleeve carried in the metal sleeve. This arguto wood sleeve forms an oil-less bearing and cooperates with the ring 44 abutting against a shoulder 44' on the armature shaft to take the thrust of the tool. It is adjustable toward this shoulder on the armature shaft by threading the metal part 41 in the casing and clamping it in place by a lock nut 46. The armature shaft 13 is hollow and extends out to the left as indicated. It carries a knurled finger grip 47 so that the operator can grip the armature shaft while adjusting the clutch rod, all of which appears more in detail in the application Serial No. 624,738, referred to above.

The end cap 40 is drilled and tapped as indicated in Figure 5 so as to receive four metal inserts 50. Each insert passes down into an annular recess 51 in the end cap and on the inner end is provided with slots 52 for cooperation with a special wrench so that it can be secured tightly in place. The threaded end of the insert extends beyond the inner face 53 of the end cap and nuts 54 having slotted heads 55 are threaded on the exposed ends of these inserts.

These nuts are employed for clamping the wires 56, 57, 58 and 59 in place as indicated in Figure 6. These wires are brought to the motor by a cable 60 which passes through a hole 61 in the wall of the end cap. The cable employed is preferably a rubber covered four conductor cable which fits close to the hole 61 in the end cap and the wires and cable are sealed in place by a quick drying varnish.

The end cap carrying the four inserts, the bearing and the cord, may be inserted in place on the armature and armature shaft by merely passing the bushing 44 along the armature shaft, then aligning the inserts 50 and screws 32 and 34, and

passing the forward end of the end cap over the brush rigging disk 29. In order that the end cap cannot be placed in the improper position, the screws 32 and 34 are arranged in asymmetric manner. As indicated in the drawings, they are all on the same radius but not on the quadrant.

In assembling the end cap, the tubular portions 35a and 36a of the nuts 35 and 36 pass into the metal inserts 50, this being facilitated by chamfering the nuts as indicated. This arrangement provides for accurately centering the screws or studs 32 or 34 in the metal inserts. Flanged nuts 62 are threaded on the exposed ends of the screws 32 and 34. These flanged nuts have slots 63 to receive a screw driver and when they are threaded down tightly as indicated in Figure 5, the flanges overlie the ends of the inserts and the end cap and brush carrying disk are secured together. In order that the electrical connections on the rear of the motor will not be exposed, a cover plate 64 may be employed. This cover plate is fastened on by screws 65. The cover plate is notched to accommodate the cord 66.

When assembling a motor of the type which has been described, the armature and field are placed in position in the motor casing with the field wires projecting out of the casing. The brush rigging disk 29 is placed in position on the end of the motor casing, field wires passed through the holes in the disk and secured to the binding posts provided by the nut on the screws 32. The brushes and springs are placed in the brush boxes and in adjusting the brush rigging to the neutral point, the motor is run with temporary connection to the screws 32 and 34, or a dummy end cap is employed. This end cap may be the same as the regular cap except that it is provided with holes to permit observation of the action of the brushes on the commutator, and is also provided with parts to engage with the brush carrying disk to permit turning the latter relative to the casing. The holes for the screws 32 are then drilled and tapped and the screws inserted.

In Figure 7 the motor casing 70 may be the same as that shown in Figures 1 and 2. The motor may be provided with the same type of commutator 12 and tubular armature shaft 13 which has been described in detail with respect to Figure 2. The motor is also adapted to carry the knurled finger grip 47 and clutch rod 14 which has been before set forth. The rear end of the armature shaft may be supported in an adjustable bearing 41.

The brush rigging disk 71 has a slightly reduced end portion 72 adapted to be inserted into the open end of the motor casing and to fit tightly in place therein. The brush rigging disk 60 is provided with a central aperture indicated at 73 to accommodate the commutator and is drilled and tapped as indicated at 74 to receive four studs. These studs are arranged in pairs, 75, 75 and 76, 76 and are disposed asymmetrically in somewhat the same manner as the screws 32 and 34. These studs are threaded into the brush rigging plate from the front or inner face and are clamped in place by lock nuts 77 which enter recesses counterbored into the rear or outer face of the brush rigging disk. The exposed ends of the studs may be smooth as indicated.

After the studs 75, 75 have been secured in place, the brush rigging disk is drilled on a diameter so as to provide brush boxes 78 which extend directly through the center of the studs 75,

as indicated. These drillings form brush boxes and are adapted to receive a brush 79, brush spring 80, and screw 81. The screws are threaded into the outer ends of the drillings suitable threads having been cut into the material so that the screws may pass below the surface of the brush rigging disk.

The wires from the motor field may be carried out through holes 82 drilled through the brush rigging disk and these field wires are placed underneath the nuts 71 carried on the studs 76 before these nuts are tightened in place.

The brush rigging is adjusted to the neutral point in the same manner that has been described and the brush rigging and motor casing fastened together by screws 85 as before described.

The end cap 86 in the construction shown in Figure 7 is somewhat similar to the end cap that has been described previously. It has a skirted portion 87 which overlies the brush rigging disk 20 and which abuts the end of the motor casing. The end cap is threaded at 88 to receive an adjustable bearing 41 and is provided with four asymmetrically arranged holes 89 threaded and counterbored to receive flanged metal inserts 90. The end cap is also drilled as indicated at 91 to receive a cable 92 similar to the cable above described and the wires extending from this cable are passed across the inner face of the end cap and secured underneath nuts 93 threaded onto the metal inserts 90. These wires and the cable are cemented in place by a quick drying varnish and in this manner the end cap with its inserts, bearing and attached cable may be assembled as a unit.

The end cap may be placed on the armature shaft and brush rigging disk of the motor in an obvious manner and then the outer ends of the studs 75 and 76 will be carried within the inserts 90. These studs are internally threaded as indicated at 94 to receive screws 95 having heads which are adapted to pass down into the counterbored holes in the end cap and against the outer end of the metal inserts. In this manner the screws 95 are employed for securing good electrical connection between the parts. To cover the screws 95, an end plate 97 may be fastened on in the same manner as the end plate 64 in the construction shown in Figure 2.

The arrangement shown in Figures 10 and 11 is designed for a motor with an end type commutator, solid shaft and current supply cord in the center. The casing 100, brush rigging disk 101, and end cap 102 are made of insulating material. The brush rigging disk 101 carries a central bearing 103, made for example of oilless wood, for the armature shaft 104. The disk is provided with two comparatively large tapped holes 105 for brush boxes 106 and two comparatively small tapped holes 107 for field connection studs 108, these holes being asymmetrically arranged as indicated in Figure 11. The disk 101 is secured to the motor casing 100, after adjustment of the brushes to the neutral position, as above described, by means of screws 109.

The brush boxes 106 have slotted heads 109 and are fixedly secured to the disk by lock washers 110. Each is drilled to receive a brush 111, a brush spring 112, and tapped to receive a screw 113. The field connection studs 108 are in the form of long screws, and locked to the disk by lock nuts 115 which also secure the field leads 116 in place.

The end cap 102 is received over the brush disk in the manner above described. It has a central

opening 117 for a four conductor current supply cord 118 which is suitably connected in place. It is drilled, tapped, and counterbored as indicated so as to receive two large inserts 129 to receive the brush boxes 106 and two smaller inserts 120 to receive the field connection studs 108. These inserts are locked in place by threaded washers 121 and 122 which also bind the appropriate wires of the cord to the proper insert.

10 The end cap, with attached cord, may be placed on the rearwardly projecting brush boxes and studs in the same manner as the cap of Figures 1-9. Nuts 123 are threaded onto the studs 108, and the brushes and brush springs inserted into 15 the brush boxes 106 and screws 124 threaded into the tapped ends of the brush boxes. The screws 124 and nuts secure the end cap in place. A cover plate 125, similar to the cover plate 64, is threaded onto the rear end of the end cap, as shown, so as to 20 cover the exposed conducting elements.

The form shown in Figures 12-16, inclusive, is designed more particularly for a Doriot type motor having a disk type commutator. The rear or open end of the motor casing is indicated at 25 130. This motor casing carries the field and front armature bearing in any suitable manner. The tubular armature shaft is indicated at 131 and the disk type commutator at 132. The tubular armature shaft 131 is adapted to receive the 30 Doriot clutch rod indicated at 133. The brush rigging disk is indicated at 134 and the end cap at 135.

The brush rigging disk has two small tapped holes as indicated at 136 for field connection members 137. These members are threaded as indicated and are provided with heads which enter counter sunk areas in the inner face of the brush disk. The outer ends of these field terminals are split as indicated at 138.

40 Field connection leads 139 are passed through holes 140 drilled in the disk and are soldered to washers 141 threaded on to the members 137.

The brush rigging disk is also provided with 45 two larger tapped holes 142 adapted to receive tubular brush boxes 143 as shown. These tubular brush boxes carry brushes 144, brush springs 145, and screws 146. The brushes bear on the commutator in the usual well known manner. The brush disk telescopes into the casing 130, as illustrated at 147, and these parts are secured together after adjusting the brush rigging to neutral position by means of screws 148.

In order to keep lubricant away from the commutator, the motor is provided with an oil thrower in the form of a flange metal sleeve 149 which snugly fits the shaft and is out of contact with the brush disk.

The end cap 135 carries a bushing 150 for the armature shaft, threaded inserts 151 adapted to receive the split pins 133, and threaded inserts 152, preferably split and adapted to frictionally receive the brush boxes or tubes 143.

The current supply cord is indicated at 155. It extends through a side opening 156 in the 65 end cap 135 and has four conductors which are carried around to the respective field connection inserts 151 and brush box receiving inserts 152, as shown in Fig. 13.

The end cap is secured to the brush carrying 70 disk by means of two screws 157 which pass through drilled and counter sunk holes 158 in the end cap, and into tapped holes 159 in the brush disk. These screws act to hold the end cap securely against the end of the motor casing and keep all the parts in proper position.

The brush springs act to press the armature toward the front end of the motor so that the thrust is normally on the front bearing, not shown. The oil thrower 149 is designed so as to just fill the space between the bushing 150 and 5 the commutator, so that the weight of the armature is kept off the brushes when the motor is operated with the rear or brush end down.

The form of construction shown in Figures 10 12-16 has the advantage of completely enclosing the field and brush connections so that no cover 15 plate is necessary. It is, however, possible to readily replace the brushes when necessary. This motor may, if desired, be enclosed in a metal shield or casing 160.

While the drawings show motors having four current carrying studs, thereby separating the field and armature circuits, it is entirely possible to omit the field connection studs and associated 20 parts where a non-reversible motor is to be constructed, and the speed is controlled by varying the applied voltage.

I claim:

1. In a miniature motor, the combination with a stationary motor casing having an open end 25 at the rear, and a revolvable armature shaft carrying a commutator, of a combined brush rigging and end cap assembly, comprising an adjustable brush rigging fixedly secured in adjusted position across the open end of the motor casing and including a brush carrying disk located to hold brushes carried thereby on the commutator, said disk also carrying rearwardly extending current carrying members, an end cap carrying a current supply cable having wires connected to terminals 35 disposed on the inner face of the end cap and spaced to cooperate with the current carrying members, a bearing carried by one of said parts for supporting one end of the armature shaft, and means including the current carrying members and independent of the bearing for securing the end cap in position.

2. In a miniature motor, the combination with a stationary motor casing having an open end at the rear, and a revolvable armature shaft 45 carrying a commutator, of a combined brush rigging and end cap assembly, comprising an adjustable brush rigging fixedly secured in adjusted position across the open end of the motor casing and including a brush carrying disk located to hold brushes carried thereby on the commutator, said disk also carrying four rearwardly extending current carrying members, two of which are connected to the brushes and two of which provide field connections, an end cap carrying a current supply cable having wires connected to each of four terminals disposed on the inner face of the end cap and spaced to cooperate with the current carrying members, a bearing carried by one of said parts for supporting one 50 end of the armature shaft, and screw threaded devices associated with the current carrying members and the terminals for securing the end cap in position.

3. In a miniature motor, the combination with a stationary motor casing having an open end at the rear, and a revolvable armature shaft carrying a commutator, of a combined brush rigging and end cap assembly, comprising an adjustable brush rigging fixedly secured in adjusted 70 position across the open end of the motor casing and including a brush carrying disk located to hold brushes carried thereby on the commutator, said disk also carrying rearwardly extending current carrying members, an end cap carrying a 75

current supply cable having wires connected to terminals disposed on the inner face of the end cap and spaced to cooperate with the current carrying members, the end cap being cup-shaped, bearing on the brush disk and abutting against the end of the motor casing, a bearing carried by one of said parts for supporting one end of the armature shaft, and means to secure the end cap in position, said current carrying members and terminals being male and female so as to slide relatively when the end cap is moved in an axial direction.

4. In a miniature motor, the combination with a stationary motor casing having an open end at the rear, and a revolvable armature shaft carrying a commutator, of a combined brush rigging and end cap assembly, comprising an adjustable brush rigging fixedly secured in adjusted position across the open end of the motor casing and including a brush carrying disk located to hold brushes carried thereby on the commutator, said disk also carrying rearwardly extending current carrying members, an end cap carrying a current supply cable having wires connected to terminals disposed on the inner face of the end cap and spaced to cooperate with the current carrying members, an axially adjustable bearing carried by the end cap for supporting one end of the armature shaft, and means to secure the end cap to the brush carrying disk.

5. In a miniature motor, the combination with a stationary motor casing having an open end at the rear, and a revolvable armature shaft carrying a commutator, of a combined brush rigging and end cap assembly, comprising an adjustable brush rigging fixedly secured in adjusted position across the open end of the motor casing and including a brush carrying disk located to hold brushes carried thereby on the commutator, said disk also carrying rearwardly extending current carrying members, an end cap carrying an eccentrically located current supply cable having wires connected to terminals disposed on the inner face of the end cap and spaced to cooperate with the current carrying members, an axially adjustable bearing carried by the end cap for supporting one end of the armature shaft, and means to secure the end cap to the brush carrying disk, the end cap with cable and bearing being removable as a unit to expose the brushes and commutator.

6. In a miniature motor, the combination with a stationary motor casing having an open end at the rear, and a revolvable armature shaft carrying a commutator, of a combined brush rigging and end cap assembly, comprising an adjustable brush rigging fixedly secured in adjusted position across the open end of the motor casing and including a brush carrying disk located to hold brushes carried thereby on the commutator, said disk also carrying rearwardly extending threaded current carrying members, an end cap carrying a current supply cable having wires connected to tubular terminals, passing through the end wall of the end cap and spaced to receive the current carrying members, a bearing carried by one of said parts for supporting one end of the armature shaft, and threaded members cooperative with the threaded current carrying members for securing the end cap in position beyond the brush carrying disk.

7. In a miniature motor, the combination with a stationary motor casing having an open end at the rear, and a revolvable armature shaft carrying a commutator, of a combined brush

rigging and end cap assembly, comprising an adjustable brush rigging fixedly secured in adjusted position across the open end of the motor casing and including a brush carrying disk located to hold brushes carried thereby on the commutator, said disk also carrying rearwardly extending threaded current carrying members, an end cap carrying a current supply cable having wires connected to tubular terminals, passing through the end wall of the end cap and spaced to receive the current carrying members, the end cap being cup-shaped, bearing on the brush disk, and abutting against the end of the motor casing, a bearing carried by one of said parts for supporting one end of the armature shaft, and threaded members cooperative with the threaded current carrying members for securing the end cap in position beyond the brush carrying disk.

8. In a miniature motor, the combination with a stationary motor casing having an open end at the rear, and a revolvable armature shaft carrying a commutator, of a combined brush rigging and end cap assembly, comprising an adjustable brush rigging fixedly secured in adjusted position across the open end of the motor casing and including a brush carrying disk located to hold brushes carried thereby on the commutator, said disk also carrying rearwardly extending threaded current carrying members, an end cap carrying a current supply cable having wires connected to tubular terminals, passing through the end wall of the end cap and spaced to receive the current carrying members, a bearing carried by one of said parts for supporting one end of the armature shaft, threaded members cooperative with the threaded current carrying members for securing the end cap in position beyond the brush carrying disk, and a cover plate of insulating material secured to the outer face of the end cap and covering the last mentioned threaded members.

9. In a miniature motor, the combination with a stationary motor casing having an open end at the rear, and a revolvable armature shaft carrying a commutator, of a combined brush rigging and end cap assembly, comprising an adjustable brush rigging fixedly secured in adjusted position across the open end of the motor casing and including a brush carrying disk located to hold brushes carried thereby on the commutator, said disk also carrying rearwardly extending current carrying members, an end cap carrying a current supply cable having wires connected to terminals disposed on the inner face of the end cap and spaced to cooperate with the current carrying members, the end cap being cup-shaped, bearing on the brush disk and abutting against the end of the motor casing, an axially adjustable bearing carried by the end cap for supporting one end of the armature shaft, and means including the current carrying members and independent of the bearing for securing the end cap in position beyond the brush carrying disk.

10. In a miniature motor, the combination with a stationary motor casing made of frangible insulating material, and a revolvable armature shaft carrying a commutator, of a combined brush rigging and end cap assembly, comprising a brush carrying disk made of frangible insulating material and having a reduced portion slidably received within the motor casing and fixedly secured to the motor casing across the end thereof and in position to hold brushes carried thereby on the commutator, a cup-shaped

end cap, also made of frangible insulating material and slidably received about the periphery of the disk, means to secure the end cap on the brush carrying disk with the end cap surrounding 5 the disk and having its edge abutting the end of the casing, the inner surfaces of the end cap and casing adjacent the edges being in contact with and reinforced by the disk, and a bearing carried by one of said parts for supporting one 10 end of the armature shaft.

11. In a miniature motor, the combination with a stationary motor casing, and a revolvable armature shaft carrying a commutator, of a combined brush rigging and end cap assembly, comprising 15 a brush carrying disk adapted to be fixedly secured to the motor casing across the end thereof and in position to hold brushes carried thereby on the commutator, an end cap, disk-supported axially extending current carrying members 20 arranged in pairs, two for the armature leads and two for the field leads, said members extending through the end cap, means cooperative with these members to secure the end cap on the brush carrying disk, the end cap having a peripheral 25 wall surrounding the disk and having its edge abutting the end of the casing, and a bearing carried by one of said parts for supporting one end of the armature shaft.

12. In a miniature motor, the combination with 30 a stationary motor casing, and a revolvable armature shaft carrying a commutator, of a combined brush rigging and end cap assembly, comprising a brush carrying disk adapted to be fixedly secured to the motor casing across the end thereof 35 and in position to hold brushes carried thereby on the commutator, an end cap, a plurality of disk-supported threaded members extending through the end cap, threaded members cooperative 40 with the end cap for securing the end cap on the brush carrying disk with the end cap surrounding the disk and having its edge abutting the end of the 45 casing, and a bearing carried by one of said parts for supporting one end of the armature shaft.

13. In a miniature motor, the combination with 50 a stationary motor casing, and a revolvable armature shaft carrying a commutator, of a combined brush rigging and end cap assembly, comprising a brush carrying disk adapted to be fixedly secured to the motor casing across the end thereof 55 and in position to hold brushes carried thereby on the commutator, an end cap supporting the armature shaft outside the brush rigging disk, and means to secure the end cap on the brush carrying disk with the end cap surrounding the disk and having its edge abutting the end of the casing.

14. In a miniature motor, the combination with 60 a stationary motor casing, and a revolvable armature shaft carrying a commutator, of a combined brush rigging and end cap assembly, comprising a brush carrying disk adapted to be fixedly secured to the motor casing across the end thereof 65 and in position to hold brushes carried thereby on the commutator, an end cap carrying current supply terminals, supporting the armature shaft outside the disk and having its edge abutting the end of the casing, and dually functioning axially extending threaded members carried by the brush 70 carrying disk and extending through the terminals on the end cap for clamping the end cap in place and conducting current to the brushes and motor field.

15. In a miniature motor, a motor casing open 75 at the rear end, a motor field carried in the cas-

ing, a motor armature shaft carrying a commutator, and a combined end cap and brush rigging assembly which provides a bearing for the armature shaft and includes an end cap and a brush rigging disk secured to the casing and carrying brushes for the commutator, brush terminals and field terminals, said terminals extending axially into corresponding terminals carried by the end cap, and securing means cooperative with the terminals for securing the end cap to the disk. 10

16. In a miniature motor, a motor casing open at the rear end, a motor field carried in the casing, a motor armature shaft carrying a commutator, and a combined end cap and brush rigging assembly which includes an end cap and a brush 15 rigging disk secured to the casing and carrying brushes for the commutator, brush terminals and field terminals, said terminals extending axially into corresponding terminals carried by the end cap, securing means cooperative with the terminals for securing the end cap to the disk, and an axially adjustable thrust bearing carried by the end cap. 20

17. In a miniature motor, a motor casing open at the rear end, a motor field carried in the casing, a motor armature shaft carrying a commutator, and a combined end cap and brush rigging assembly which provides a bearing for the armature shaft and includes an end cap and a brush 25 rigging disk secured to the casing and carrying brushes for the commutator, brush terminals and field terminals, said terminals extending axially into corresponding terminals carried by the end cap, the end cap telescopically fitting the disk and having its end engaging the open end of the casing, and securing means cooperative with the terminals for securing the end cap to the disk. 30

18. In a miniature electric motor, in combination, a cup-shaped end cap, a brush rigging disk telescopically fitting inside the end cap and carrying a pair of brush lead studs and a pair of field lead studs, all the studs extending rearwardly and passing through metal inserts in the end cap, and threaded members cooperative with the outside of the end cap and the studs for 40 securing the end cap to the brush rigging disk. 45

19. In a miniature electric motor, in combination, a cup-shaped end cap, a brush rigging disk telescopically fitting inside the end cap and carrying a pair of brush lead studs and a pair of field lead studs, all the studs extending rearwardly and passing through metal inserts in the end cap, threaded members cooperative with the outside of the end cap and the studs for securing the end cap to the brush rigging disk, and a shaft bearing carried by one of said parts for the armature shaft. 50

20. In a miniature electric motor, in combination, a cup-shaped end cap, a brush rigging disk telescopically fitting inside the end cap and carrying a pair of brush lead studs and a pair of field lead studs, all the studs extending rearwardly and passing through metal inserts in the end cap, threaded members cooperative with the outside of the end cap and the studs for securing the end cap to the brush rigging disk, and an axially adjustable armature shaft bearing carried by the end cap. 65

21. The combination with a cylindrical motor casing of rigid self-sustaining insulating material 70 and having its open end in a plane normal to the cylinder axis, of a brush rigging disk of insulating material telescopically fitting inside and secured to the casing, and having a shoulder in a plane normal to the disk axis and abutting 75

- against the inner margin of the end wall of the casing to limit the movement of the disk along the casing axis and to insure that the axis of the disk coincides with the axis of the casing, and an end cap telescopically fitting the outside of the brush rigging disk and coaxial therewith, the edge of the end cap being normal to the plane of the cap axis and abutting against the end wall of the motor casing whereby the disk and cap may be adjusted about the casing axis. 10
22. The combination with a cylindrical motor casing of rigid self-sustaining insulating material and having its open end in a plane normal to the cylinder axis, of a brush rigging disk of insulating material telescopically fitting inside and secured to the casing, and having a shoulder in a plane normal to the disk axis and abutting against the inner margin of the end of the casing to limit the movement of the disk along the casing axis and to insure that the axis of the disk coincides with the axis of the casing, and an end cap telescopically fitting the outside of the brush rigging disk and coaxial therewith, the edge of the end cap being normal to the plane of the cap axis and abutting against the end wall of the motor casing whereby the disk and cap may be adjusted about the casing axis, the disk having radial brush boxes which are covered by the end cap. 25
- 30 23. The combination with a cylindrical motor casing of rigid self-sustaining insulating material, of a brush rigging disk of insulating material telescopically fitting inside and secured to the casing, and having a shoulder abutting against the inner margin of the end of the casing, an end cap telescopically fitting the outside of the brush rigging disk and abutting against the end wall of the motor casing, pairs of studs attached to the disk for supplying current to the armature and field, said studs passing through the end cap, and devices threaded on the exposed ends of the studs for securing the end cap in place. 35
24. In an electric motor, a brush rigging disk, a pair of rearwardly extending armature lead studs carried by the disk and connected with brushes for cooperation with the motor commutator, a pair of rearwardly extending field connection studs carried by the disk, an end cap having four metal sleeves each connected to a current supply wire, and adapted to receive one of the studs, and means cooperative with the studs for securing the end cap in place. 45
- 55 25. In an electric motor, a brush rigging disk, a pair of rearwardly extending armature lead studs carried by the disk and connected with brushes for cooperation with the motor commutator, a pair of rearwardly extending field connection studs carried by the disk, an end cap having four metal sleeves each connected to a current supply wire and adapted to receive one of the studs, the end cap also having a peripheral skirt which surrounds the disk, and means cooperative with the studs for securing the end cap in place. 60
- 65 26. In an electric motor, a brush rigging disk, a pair of rearwardly extending armature lead studs carried by the disk and radially drilled to provide boxes for brushes for cooperation with the motor commutator, a pair of rearwardly extending field connection studs carried by the disk, an end cap having four metal sleeves each connected to a current supply wire and adapted to receive one of the studs, and threaded mem- 70
- bers carried by the studs for securing the end cap in place. 75
27. An end cap for miniature motors comprising a rigid self-sustaining cup-shaped body of insulating material having a plurality of threaded holes extending through the end wall of the end cap, flanged metal tubular inserts threaded into the holes, the outer face of the end cap being recessed to receive the flanges, the inserts extending beyond the inner face of the end wall of the cap, and a cable passing through the end wall and having wires, each of which is secured to the exposed end of an insert. 10
- 15 28. An end cap for miniature motors comprising a rigid self-sustaining cup-shaped body of insulating material having a plurality of threaded holes extending through the end wall of the end cap, flanged metal tubular inserts threaded into the holes, the outer face of the end cap being recessed to receive the flanges, the inserts extending beyond the inner face of the end wall of the cap and being slotted to receive a screw driver to permit tightening them from the inside, nuts threaded onto the ends of the inserts, and a cable passing through the end wall and having wires, each of which is secured underneath a nut. 20
- 20 29. In a miniature electric motor of the type wherein a shaft driven tool is connected to the motor casing and driven from the front end of the motor, an end cap for the rear end of the motor in the form of a rigid self-sustaining cup-shaped body of insulating material carrying a plurality of tubular metal inserts spaced about the motor axis, and extending through its end wall, and a cable passing through a hole in said end wall and having a wire secured to each insert. 25

rality of axially extending threaded holes arranged in pairs, a pair of metallic studs secured in said holes and extending rearwardly from the annulus, there being a radially extending drilling extending through the annulus and each stud, brushes and brush springs disposed in said drillings, and plugs in the outer ends of the drillings to retain the brushes and springs in place.

34. A brush rigging for miniature motors comprising an annulus of insulating material having a central opening for a commutator, a forwardly extending peripheral skirt adapted to be received in a motor casing and a plurality of axially extending threaded holes arranged in pairs, a pair 10 of metallic studs threaded through said holes extending rearwardly from the annulus and locked therein, there being a radially extending drilling extending through the annulus and each stud, brushes and brush springs disposed in said drillings, and plugs in the outer ends of the drillings 15 to retain the brushes and springs in place.

35. A brush rigging for miniature motors comprising an annulus of insulating material having a central opening for a commutator, a forwardly 20 extending peripheral skirt adapted to be received in a motor casing, and a plurality of axially extending threaded holes arranged in pairs, a pair of metallic studs threaded through said holes extending rearwardly from the annulus 25 and locked therein, there being a radially extending drilling extending through the annulus and each stud to provide a brush box, and a pair of field connection studs secured in the other pair of threaded holes and extending rearwardly from 30 the annulus, all said studs having tapped holes at their rear ends to receive end cap supporting 35 screws.

36. A brush rigging for miniature motors comprising an annulus of insulating material having 40 a central opening for a commutator, a forwardly extending peripheral skirt adapted to be received in a motor casing and a plurality of axially extending threaded holes arranged in pairs, a pair of metallic studs threaded through said holes extending rearwardly from the annulus and locked 45 therein, there being a radially extending drilling extending through the annulus and each stud, brushes and brush springs disposed in said drillings, plugs in the outer ends of the drillings to 50 retain the brushes and springs in place, and a pair of field connection studs secured in the other pair of threaded holes and extending rearwardly from the annulus, the annulus having apertures to allow passing field wires through it for securing 55 to the last mentioned studs, all said studs having tapped holes at their rear ends to receive end cap supporting screws.

37. A brush rigging for miniature electric motors comprising an annular disk of insulating 60 material having an opening to receive a commutator, and a pair of metallic members axially extending through the disk and secured to it, there being a radial drilling through the disk and members to provide brush boxes.

65 38. In a miniature motor, the combination with a stationary motor casing having an open end at the rear, and a revolvable armature shaft carrying a commutator, of a combined brush rigging and end cap assembly comprising an adjustable 70 brush rigging fixedly secured in adjusted position across the open end of the motor casing and including a brush carrying disk located to hold brushes carried therein on the commutator, said disk also carrying rearwardly extending current 75 carrying pins and a central bearing for the arma-

ture shaft, an end cap carrying a current supply cable extending out through the center of the end cap, tubular terminals disposed on the inner face of the end cap, connected to the wires of the cable, and spaced to cooperate with the current carrying pins, and means to secure the end cap in position beyond the brush carrying disk. 5

39. In a miniature motor, the combination with a stationary motor casing having an open end at the rear, and a revolvable armature shaft carrying a disk type commutator, of a combined brush rigging and end cap assembly comprising an adjustable brush rigging fixedly secured in adjusted position across the open end of the motor casing and including a brush carrying disk having radially extending brush boxes so located to hold brushes carried therein on the commutator, said disk also carrying rearwardly extending current carrying pins and a central bearing for the armature shaft, an end cap carrying a current supply 10 cable extending out through the center of the end cap, tubular terminals disposed on the inner face of the end cap connected to the wires of the cable, and spaced to cooperate with the current 15 carrying pins, and means to secure the end cap in position beyond the brush carrying disk. 20

40. In a miniature motor, a motor casing open at the rear end, a motor field carried in the casing, a motor armature carrying a cylindrical commutator, and a combined end cap and brush 30 rigging assembly which includes a brush rigging disk secured to the casing and carrying brushes disposed in radial brush boxes and cooperative with the commutator, brush terminals and field terminals, and a bearing for the armature shaft, 35 and an end cap having tubular terminals into which the first terminals axially extend and means cooperative with the terminals for securing the end cap to the disk.

41. In a miniature electric motor, in combination, a cup-shaped end cap, a brush rigging disk telescopically fitting inside the end cap and carrying a pair of brush lead studs and a pair of field lead studs, all the studs extending rearwardly and passing through metal inserts in the 45 end cap, threaded members cooperative with the outside of the end cap and the studs for securing the end cap to the brush rigging disk, a bearing for the armature shaft mounted in the disk, and a current supply cable passing through the center 50 of the end cap and having wires secured to the inserts.

42. An end cap for miniature motors made of insulating material and having axially extending radially disposed metallic inserts, the end cap 55 being recessed so that the inserts are below the surface of the end cap, the end cap having a threaded boss, and an insulating cover plate threaded on the boss.

43. An end cap for miniature motors made of insulating material and having axially extending radially disposed metallic inserts, the end cap being recessed so that the inserts are below the surface of the end cap, the end cap having a threaded boss, and an insulating cover plate 65 threaded on the boss, the boss being tubular to accommodate a current supply cable.

44. In a miniature motor, the combination with a stationary motor casing having an open end at the rear, and a revolvable armature shaft carrying a disk type commutator, of a combined brush rigging and end cap assembly comprising an adjustable brush rigging fixedly secured in adjusted position across the open end of the casing and including a brush carrying disk having tubular 75

brush boxes axially disposed therein on opposite sides of the bearing, and an end cap carrying a current supply cable connected to tubular terminals disposed on the inner face of the end cap and spaced to receive the brush boxes.

45. In a miniature motor, the combination with a stationary motor casing having an open end at the rear, and a revolvable armature shaft carrying a disk type commutator, of a combined brush 10 rigging and end cap assembly comprising an adjustable brush rigging fixedly secured in adjusted position across the open end of the casing and including a brush carrying disk having outwardly opening tubular brush boxes axially disposed thereon on opposite sides of the shaft axis, an end cap carrying a current supply cable connected to tubular terminals disposed on the inner face of the end cap and spaced to receive the brush boxes, and means for securing the end cap 15 on the disk and against the end of the casing, said means being in addition to the brush boxes whereby the brushes may be removed for inspection without removing the end cap.

46. In a miniature motor, the combination with 20 a stationary motor casing having an open end at the rear, and a revolvable armature shaft carrying a disk type commutator, of a combined brush rigging and end cap assembly comprising an adjustable brush rigging fixedly secured in adjusted position across the open end of the casing and including a brush carrying disk having tubular brush boxes axially disposed therein on opposite sides of the shaft axis, an end cap carrying a current supply cable connected to tubular 25 terminals disposed on the inner face of the end cap and spaced to receive the brush boxes, and screws threaded into the brush boxes and cooperative with the end cap for securing the end cap in position and holding the brushes in the brush boxes.

47. In a miniature motor, the combination with a stationary motor casing having an open end at the rear, and a revolvable armature shaft carrying a disk type commutator, of a combined brush 30 rigging and end cap assembly comprising an adjustable brush rigging fixedly secured in adjusted position across the open end of the casing and including a brush carrying disk having axially disposed threaded openings on opposite sides 35 of the shaft axis, tubular brush boxes threaded into the openings and projecting rearwardly, an end cap carrying a current supply cable connected to tubular terminals disposed on the inner face of the end cap and spaced to receive the brush boxes, and screws threaded into the brush 40 boxes and cooperative with the end cap for securing the end cap in position and holding the brushes in the brush boxes.

48. In a miniature motor, a motor casing open 45 at the rear end, a motor field carried in the casing, a motor armature shaft carrying a disk type commutator, and a combined end cap and brush rigging assembly which provides a bearing for the armature shaft and includes an end cap and brush rigging disk secured to the casing and carrying 50 axially extending tubular terminals for brushes for the commutator, and field terminals, said terminals extending axially into corresponding terminals carried by the end cap, and means 55 for securing the end cap to the disk.

49. In a miniature motor, a motor casing open 60 at the rear end, a motor field carried in the casing, a motor armature shaft carrying a disk type commutator, and a combined end cap and brush rigging assembly which provides a bearing for 65

the armature shaft and includes an end cap and brush rigging disk secured to the casing and carrying axially extending tubular terminals for brushes for the commutator, and field terminals, said terminals extending axially into corresponding terminals carried by the end cap, and nuts threaded on the field terminals for securing the end cap to the disk. 70

50. In a miniature motor, a motor casing open at the rear end, a motor field carried in the casing, 10 a motor armature shaft carrying a disk type commutator, and a combined end cap and brush rigging assembly which provides a bearing for the armature shaft and includes an end cap and brush rigging disk secured to the casing and carrying 15 axially extending tubular terminals for brushes for the commutator, and field terminals, said terminals extending axially into corresponding terminals carried by the end cap, and screws threaded to the tubular terminals for holding 20 brushes therein.

51. In a miniature electric motor, in combination, a cup-shaped end cap, a brush rigging disk telescopically fitting inside the end cap and carrying a pair of field connection studs and a pair 25 of tubular brush boxes, the studs and boxes extending rearwardly and passing through metal inserts in the end cap, and threaded members cooperative with the outside of the end cap and the ends of the studs and boxes for securing the 30 end cap to the disk, the brush box securing members also securing brushes in the brush boxes.

52. The combination with a cylindrical motor casing of rigid self-sustaining insulating material, of a brush rigging disk of insulating material tele- 35 scopically fitting inside and secured to the casing, and having a shoulder abutting against the inner margin of the end of the casing, and an end cap telescopically fitting the outside of the brush rigging disk and abutting against the end wall 40 of the motor casing, the disk having axially extending brush boxes extending into inserts in the end cap.

53. In a miniature motor, the combination with a stationary motor casing and a revolvable armature shaft carrying a disk type commutator, of a brush carrying disk secured across the end of the casing, a pair of tubular brush boxes carried by the disk and projecting rearwardly from the disk, brushes and brush springs in each brush box, a retaining screw for holding the brushes and springs in place, a cup-shaped end cap having tubular metal inserts adapted to frictionally receive the ends of the brush boxes, a current supply wire secured to each insert, and screws passing through 55 the end cap and threaded into the brush disk for securing the end cap against the end of the motor casing.

54. A miniature motor as claimed in claim 44, characterized in that the end cap covers and conceals the inserts so that current carrying parts are absent from the rear face of the end cap, and wherein the end cap is secured to the brush rigging disk by axially extending screws threaded into the disk. 60

55. In a miniature motor, a brush rigging disk made of insulating material and adapted to be secured across the open end of a motor casing, and two tubular metallic brush boxes secured to the disk and adapted to hold brushes against a 70 disk type commutator disposed within the casing, said brush boxes extending rearwardly from the disk, threaded members carried by the boxes for holding brushes therein, and an end cap made of insulating material and telescopically received by 75

the disk and having tubular inserts carried in sockets for frictionally receiving the brush boxes.

56. In a miniature motor, a motor casing open at the rear end, a motor field carried in the casing, a motor armature shaft carrying a disk type commutator, and a combined end cap and brush rigging assembly which provides a bearing for the armature shaft and includes an end cap and

brush rigging disk secured to the casing and carrying axially extending tubular terminals for brushes for the commutator, and field terminals, said terminals extending axially into corresponding terminals carried by the end cap, and means independent of the conducting parts for securing the end cap to the disk. 5

HOWARD A. WHITESIDE.
